[57] **CLAIM**

The ornamental design for a combined swimming pool cover-roller and brake, substantially as shown and described.

DESCRIPTION

FIG. 1 is a front perspective view of a combined swimming pool cover-roller and brake showing my new design, and wherein the broken lines indicate the cover being rolled;

FIG. 2 is a plan view as seen from the top of FIG. 1 with the central portion shown broken away for convenience of illustration;

FIG. 3 is an elevational view as seen from the right of FIG. 1; and

FIG. 4 is an enlarged view taken approximately between the bracket indicated as 4 in FIG. 1 but with the tab raised for purpose of illustration.

The cover is shown in broken lines in FIG. 1 for illustrative purposes only and does not form part of the claimed design.

The arrow shown at the left end of FIG. 1 indicates the direction of turning and in FIG. 4 the swing of the tab.

FIG. 3

FIG. 2
